Application January 10, 1956, Serial No. 558,288

8 Claims. (Cl. 250—83.6)

This invention relates generally to ion discharge apparatus wherein the discharges are initiated by electromagnetic radiations, as, say, X-rays, ultraviolet rays, visible light, or infrared rays. More particularly, this invention relates to ion discharge apparatus of this character wherein an input pattern of radiation to the apparatus causes ionization therein in a localized plasma region whose configuration reproduces the pattern of the radiation received by the apparatus.

It is an object of the invention to provide apparatus capable of selectively identifying or recognizing a large number of different radiation patterns received by the apparatus.

It is another object of the invention to provide apparatus of the above-noted character wherein the different radiation patterns are distinctively indicated by different combinations of electrical indications.

These and other objects are realized according to the invention by providing apparatus comprising, a first electrode of sizable extent in two coordinates of a three coordinate system for measuring space, a second electrode coextensive with the first electrode in the named two coordinates and spaced from the first electrode in the direction of the third coordinate, and a closure means which maintains an ionizable medium in the space between the two electrodes. The first electrode is pervious to ionizing radiation of the sort described above. A voltage source is coupled between the first electrode and the second electrode to render the intervening medium ionizable by radiation which penetrates the first electrode. The spacing between the electrodes, the nature of the ionizable medium, and the value of voltage applied across the electrodes are such that a pattern of radiation penetrating the first electrode will ionize the medium only in a localized plasma region whose pattern duplicates the pattern of the incoming radiation.

To determine the configuration of the localized plasma region, there is provided a plurality of at least three sensing electrodes disposed in the medium at points which are distributively spaced in the first-mentioned two coordinates to form a network of plasma sensing points. An electric energy source energizes all of the sensing electrodes at a voltage lower than the ionizing voltage for the medium. Since a plasma region is a low impedance region, the electric energy source will cause current to flow through the ones of the sensing electrodes in contact with the plasma in a plasma pattern formed in the medium by the received radiation pattern. The current flow through sensing electrodes having no contact with the plasma of the plasma pattern will be negligible at the best inasmuch as a very high impedance to current flow is offered by the medium outside of the plasma pattern. Since the locations of all the sensing electrodes are known, it is only necessary to determine which of the sensing electrodes have current passing therethrough in order to determine in a general manner the pattern of the plasma. This determination of current flow is made by suitable current responsive indicator

means. It will be appreciated that the number of sensing electrodes can be increased as desired, and the mutual spacing between sensing electrodes be conversely decreased as desired to increase the accuracy with which 5 the shape of the plasma pattern can be determined.

For a better understanding of the invention, reference is made to the following description of an exemplary embodiment of the invention, the description to be taken with the accompanying drawings wherein:

10 Fig. 1 is a front view of an embodiment according to the invention;

Fig. 2 is a view of the said embodiment taken in cross section as indicated by the arrows 2—2 in Fig. 1;

Fig. 3 is an enlarged view in cross section of a portion 15 of the view in Fig. 2; and

Fig. 4 is a schematic diagram of certain of the electrical connections of the said embodiment.

Referring now to Figs. 1 and 2, the number 10 designates a glass plate whose left-hand face, as seen in Fig. 2, is rendered electroconductive by depositing a coating 11 of an electroconductive material (as, say, zinc oxide) on the face, and by then fusing the coating 11 into the glass 10. The plate 10 and coating 11 together represent the mentioned first electrode which is pervious to ionizing radiation. The presently-described embodiment is adapted to identify radiation patterns formed by visible light, and, to this end, both the glass plate 10 and the coating 11 are light transparent.

Disposed in spaced parallel relation from the plate 10 is an insulating plate 15 having deposited on the face thereof towards plate 10 a coating 16 of high impedance electroconductive material, as, say, carbon. This coating 16 represents the mentioned second electrode. The plate 15 is penetrated by a plurality of low impedance 30 (e.g. metallic) rod electrodes 17a, 17b, 17c, 17d and 17e (Fig. 1). As shown, the rod electrode 17a occupies a central position, and the rod electrodes 17b-17e are symmetrically disposed about the electrode 17a. Each of the rod electrodes extends through and beyond the insulating plate member 15 towards the glass plate 10. Preferably, the electrodes 17a-17e extend towards plate 10 no further than to be in flush relation with the outer surface of the high impedance electroconductive coating 16. As best shown in Fig. 3, voids are left in the coating 16 40 in localized areas thereof which respectively surround the rod electrodes.

The plates 10 and 15 are held in spaced apart relation by a gasket 20 which encircles the respective peripheries of the plates. The gasket 20 additionally acts as 50 a closure means to maintain an ionizable medium 21 in the space between the plates 10 and 11. The medium 21 may consist, for example, of a mixture of nitrogen and argon reinforced by a small percentage of a gaseous quenching compound such as ether vapor or vapors of 55 suitable alcohols. The ionizable medium 21 may be hermetically sealed in the space between the plates 10 and 15 by the gasket 20. For better operation of the apparatus, it is preferable, however, to have the medium in this space replenishable from an outside reservoir 60 (not shown) of the medium.

In respect to electrical connections, a voltage source represented by a battery 25 has its negative terminal connected to the electroconductive surface 11 of plate 10, and its positive terminal connected through a current limiting resistor 26 to the high impedance electroconductive coating 16 on plate 15. As best shown in Fig. 4, the several rod electrodes 17a-17e are respectively connected to the coating 16 through a plurality of high impedance paths furnished, for example, by a plurality 65 of resistors 27a-27e. The purpose of resistors 27a-27e is to tie the static potential on rod electrodes 17a-17e to the static potential of coating 16 to thus establish the 70

same reference potential for both the rod electrodes and the coating.

The rod electrodes 17a-17e are adapted to act as sensing electrodes by virtue of an interconnection thereof wherein an electric energy source 30 has one end connected to the electrode 17a, and its other end connected to all of the other electrodes 17b-17e. The source 30 may be a D.C. source whose voltage is less than the ionizing voltage for medium 21. For example, source 30 may provide a 4-10 volt output when the ionizing voltage for the medium is 60-75 volts. Source 30 may also be an A.C. source whose peak voltage is less than the ionizing voltage value for the medium and whose frequency is substantially higher than the frequency of the operations which the described embodiment is called upon to perform.

A plurality of current responsive indicator means are respectively interposed in circuit between the electrodes 17b-17e and the source 30. In Fig. 4, these current responsive indicator means are shown as the ammeters 31b-31e. It will be appreciated, however, that relays or other current responsive devices could be substituted for the shown ammeters.

The described embodiment operates in the following manner. A pattern formed by visible light is projected by an optical system (not shown) towards the glass plate 10. This pattern may, for example, have a configuration whose outline is represented by the outline of the stippled area 35 of Fig. 1. The light in this pattern penetrates the glass plate 10 and the transparent electroconductive coating 11 to enter the ionizable medium 21.

The light passing through plate 10 and coating 11 will initially produce an ionized condition of the medium 21 within the bounds of the pattern formed by the light. In an ordinary ionization chamber, this ionized condition would almost immediately spread throughout the whole space occupied by the medium between the electrodes 11 and 16. The presently disclosed embodiment is, however, constructed in accordance with the teachings of Kurt S. Lion (in his article "Electronic Photography" in the December 1953 issue of Research Reviews published by the Office of Naval Research, Department of the Navy, Washington, D.C.), who has found that with a suitable spacing between and a suitable voltage applied between a pair of opposing electrodes in a suitable ionizing medium, it is possible to initiate an ion discharge in the medium at a given point in a plane parallel to the electrode faces, and to have this ion discharge remain substantially localized at its point of initiation rather than spreading out through an area of the plane which is coextensive with the electrode face areas. In general, the transverse area occupied by any such ion discharge initiated at a point is of the same order as the longitudinal spacing between the electrodes. While it is not entirely necessary to use a quencher in the medium, it has been found that the transverse area occupied by a localized ion discharge can be reduced if such quencher is used, and if the voltage applied between the electrodes is adjusted to a value which produces self-quenching of the ion discharge. This advantage of a reduced transverse area by self-quenching may be obtained in what is apparently a continuously subsisting localized ion discharge by continuously renewing the self-quenching discharge at the point of initiation with radiation which falls on the point of initiation throughout a time period which is as long as desired.

From what has been said, it will be seen that the light pattern entering medium 21 will ionize this medium in a localized plasma region 35 (Figs. 1 and 2) whose outline corresponds to a close approximation to the outline of the light pattern itself. Different light patterns will produce different plasma regions within the medium 21. For example, the plasma region 35 shown in Figs. 1 and 2 surrounds and connects the sensing electrodes 17a, 17b, but does not surround the other sensing elec-

trodes 17c-17e so as to connect these electrodes by a plasma path. Other light patterns will produce a plasma path exclusively between, say, electrodes 17a and 17c, or between, say, electrodes 17a, 17c and 17e.

Ordinarily the medium 21 offers a high impedance to flow of current between the electrode 17a and any one or more of the electrodes 17b-17e. When, however, a plasma path is created between electrode 17a and any one of the other electrodes this plasma path acts as a low impedance path for current flow between the two electrodes, and this current flow will take place despite the fact that the voltage between the two sensing electrodes may be considerably less than the ionizing voltage for the medium 21. Thus, the plasma region 35 (Figs. 1 and 2) which straddles the electrodes 17a and 17b provides a low impedance path between these electrodes such that the voltage developed across these electrodes by voltage source 30 will cause a substantial current flow through the plasma region 35 and through both of these electrodes. This substantial current flow causes a marked indication to appear on ammeter 31b in circuit with the electrodes 17a and 17b. None of the other ammeters will, in this instance, produce any substantial indication inasmuch as none of the other electrodes 17c-17e are connected to the electrode 17a through a plasma path.

From what has been said, it will be seen that differently shaped plasma regions induced by (and duplicating) differently shaped radiation patterns incident on the described embodiment will be indicated by different combinations of readings of the ammeters 31b-31e. For example, any one of these ammeters may give a reading while the other ammeters are absent a reading. Also, any two of the ammeters may give a reading while the other two ammeters are absent a reading. Also, any three of the ammeters may give a reading while the remaining ammeter is absent a reading, or all four ammeters may give a reading. It is thus possible with the presently described embodiment to obtain different combinations of electrical indications which separately identify 15 different radiation patterns. It will moreover be evident that, by utilizing additional voltage sources 30 connected to urge current flow among any two of the electrodes 17b-17e, by utilizing additional current responsive indicator means to indicate each such current flow, and by taking proper precautions to assure that each current between a given two sensing electrodes operates one and only one indicator means, it is possible to identify many more radiation patterns than the 15 just mentioned.

In view of the mode of operation of the above-described embodiment, the purpose of certain features thereof will be more apparent. For example, the rod electrodes 17a-17e extend no further than the outer surface of coating 16 in order to avoid favored locations of ion discharge because of shorter ionization gaps between coating 11 and the rod electrodes than between the coating 11 and coating 16. Also, voids are left in coating 16 in localized areas thereof surrounding the rod electrodes in order to increase the impedance between each of electrodes 17b-17e and electrode 17a in the absence of a plasma bridge connecting the last-named electrode with one or more of the first-named electrodes. Also, the source 30 provides a voltage of less than the ionizing voltage value for medium 21 in order to prevent ionization of the medium by the voltage between the rod electrodes represented by coatings 11 and 16.

The above-described embodiment being exemplary only, it will be understood that the invention herein comprehends inventions differing in form or detail from the above-described embodiment. Accordingly, the invention is not to be considered as limited save as is consonant with the scope of the following claims.

I claim:

1. Radiation pattern identifying apparatus comprising, a first electrode of sizable extent in two coordinate directions, said electrode being pervious to ionizing radiation, an insulating member coextensive with said first electrode in said two directions and spaced therefrom in the third coordinate direction in an amount substantially less than the extent of said electrodes in either of said two coordinate directions, a coating of high impedance electroconductive material in the nature of a second electrode deposited on the face of said member towards said first electrode, said coating being void of such material in localized areas respectively surrounding a plurality of at least three points distributively spaced over said member to form a network of plasma sensing points, closure means to maintain an ionizable medium in the space between said electrodes, an ionizing voltage source coupled between said electrodes to render said medium ionizable in a localized plasma pattern by and in accordance with a pattern of ionizing radiation which penetrates said first electrode, a plurality of sensing electrodes in the form of low impedance rods respectively located in said two coordinate directions at said sensing points and extending through said second electrode towards said first electrode to terminate at a distance from said first electrode which at the least is equal to the distance therefrom of said second electrode, a plurality of high impedance paths respectively connecting said sensing electrodes to said second electrode to establish the potential of the latter as the reference potential for the former, electric energy source means for energizing said sensing electrodes to produce substantial current flow at less than ionizing voltage for said medium through the ones of said sensing electrodes in contact with the plasma of a plasma pattern produced in said medium, and means to indicate which sensing electrodes have current flowing therethrough.

2. Radiation pattern identifying apparatus comprising, a first electrode of sizeable extent in two coordinate directions, said electrode being pervious to ionizing radiation, an insulating member coextensive with said first electrode in said two directions and spaced therefrom in the third coordinate direction in an amount substantially less than the extent of said electrodes in either of said two coordinate directions, a coating of high impedance electroconductive material in the nature of a second electrode deposited on the face of said member towards said first electrode, said coating being void of such material in localized areas respectively surrounding a plurality of at least three points distributively spaced over said member to form a network of plasma sensing points, closure means to maintain an ionizable medium in the space between said electrodes, an ionizing voltage source coupled between said electrodes to render said medium ionizable in a localized plasma pattern by and in accordance with a pattern of ionizing radiation which penetrates said first electrode, a plurality of sensing electrodes in the form of low impedance rods respectively located in said two coordinate directions at said sensing points and extending through said second electrode towards said first electrode to terminate at a distance from said first electrode which at the least is equal to the distance therefrom of said second electrode, a plurality of high impedance paths respectively connecting said sensing electrodes to said second electrode to establish the potential of the latter as the reference potential for the former, a source of voltage of less than the ionizing value for said medium connected by one terminal to one of said sensing electrodes and by the other terminal to the others of said sensing electrodes, and a plurality of current responsive indicator means respectively interposed between said source and said other electrodes to indicate which thereof have current flowing therethrough.

3. Radiation pattern identifying apparatus comprising, first electrode means of sizeable extent in two coordinate

directions and providing a discharge area of continuous extent between opposite outside bounds of said area, said first electrode means being of thinner extent in the third coordinate direction than either dimension of said area, 5 and being subject in said discharge area to penetration by ionizing radiation, second electrode means spaced from said first electrode means in the third coordinate direction by an extent less than either dimension of said discharge area of said first electrode means said second electrode means having a discharge area coextensive with that of said first electrode means, an ionizable medium disposed in the space between said discharge areas and adapted to be ionized in a localized plasma pattern by and as a replica of a pattern of said penetrating ionizing 15 radiation to thereby sustain an electrical discharge between the discharge areas of said first and second electrode means, and a plurality of at least three sensing electrodes electrically insulated from each of first and second electrode means and respectively disposed in said 20 medium at points which are distributively spaced in said two coordinate directions to form a network of plasma sensing points, said network extending in both of said two directions, and the points thereof being separated by straight line intervals lying within the bounds in said 25 two directions of said discharge areas.

4. Radiation pattern identifying apparatus comprising, first electrode means of sizeable extent in two coordinate directions and providing a discharge area of continuous extent between opposite outside bounds of said area, said 30 first electrode means being of thinner extent in the third coordinate direction than either dimension of said area, and being subject in said discharge area to penetration by ionizing radiation, second electrode means spaced from said first electrode means in the third coordinate direction by an extent less than either dimension of said discharge area of said first electrode means, said second electrode means having a discharge area coextensive with that of said first electrode means, an ionizable medium disposed in the space between said discharge areas and adapted to be ionized in a localized plasma pattern by and as a replica of a pattern of said penetrating ionizing 35 radiation to thereby sustain an electrical discharge between the discharge areas of said first and second electrode means, and a plurality of at least three sensing electrodes in the form of rods electrically insulated from each of said first and second electrode means and extending through said second electrode means at respective points which are distributively spaced in said two coordinate directions to form a network of plasma sensing points, 40 said network extending in both of said two directions, and the points thereof being separated by straight line intervals lying within the bounds in said two directions of said discharge areas, said sensing electrodes terminating at a distance from said first electrode means which at the least 45 is equal to the distance therefrom of said first electrode means.

5. Apparatus as in claim 4 wherein said sensing electrodes are electrically insulated from said second electrode means by voids formed in said second electrode means in the localized regions thereof which respectively surround said sensing electrodes.

6. Radiation pattern identifying apparatus comprising, first electrode means of sizeable extent in two coordinate directions and providing a discharge area of continuous extent between opposite outside bounds of said area, said 65 first electrode means being of thinner extent in the third coordinate direction than either dimension of said area, and being subject in said discharge area to penetration by ionizing radiation, second electrode means spaced from said first electrode means in the third coordinate direction by an extent less than either dimension of said discharge area of said first electrode means, said second electrode means having a discharge area coextensive with that of said first electrode means, an ionizable medium disposed 70 in the space between said discharge areas and adapted

to be ionized in a localized plasma pattern by and as a replica of a pattern of said penetrating ionizing radiation to thereby sustain an electrical discharge between the discharge areas of said first and second electrode means, a plurality of at least three sensing electrodes electrically insulated from each of first and second electrode means and respectively disposed in said medium at points which are distributively spaced in said two coordinate directions to form a network of plasma sensing points, said network extending in both of said two directions, and the points thereof being separated by straight line intervals lying within the bounds in said two directions of said discharge areas, electrical energy source means connected with said sensing electrodes to produce substantial current flow at less than ionizing voltage for said medium between ones of said sensing electrodes in contact with the plasma of a plasma pattern produced in said medium, and means to indicate which sensing electrodes have current flowing therethrough.

7. Radiation pattern identifying apparatus comprising, first electrode means of sizeable extent in two coordinate directions and providing a discharge area of continuous extent between opposite outside bounds of said area, said first electrode means being of thinner extent in the third coordinate direction than either dimension of said area, and being subject in said discharge area to penetration by ionizing radiation, second electrode means spaced from said first electrode means in the third coordinate direction by an extent less than either dimension of said discharge area of said first electrode means, said second electrode means having a discharge area coextensive with that of said first electrode means, an ionizable medium disposed in the space between said discharge areas and adapted to be ionized in a localized plasma pattern by and as a replica of a pattern of said penetrating ionizing radiation to thereby sustain an electrical discharge between the discharge areas of said first and second electrode means a voltage source coupled between said first and second electrode means to produce said discharge when said medium becomes ionized, a plurality of at least three sensing electrodes electrically insulated from each of first and second electrode means and respectively disposed in said medium at points which are distributively spaced in said two coordinate directions to form a network of plasma sensing points, said network extending in both of said two directions, and the points thereof being separated by straight line intervals lying within the bounds in said two directions of said discharge areas, electrical energy source means connected with said sensing electrodes to produce substantial current flow at less than ionizing voltage for said medium between ones of said sensing electrodes in contact with the plasma of a plasma pattern

produced in said medium, means to indicate which sensing electrodes have current flowing therethrough, and a high impedance path electrically connecting said voltage source and said electrical energy source means.

- 5 8. Radiation pattern identifying apparatus comprising, first electrode means of sizable extent in two coordinate directions and providing a discharge area of continuous extent between opposite outside bounds of said area, said first electrode means being in the form of a transparent 10 electroconductive conducting on a transparent insulating substrate member, whereby said first electrode means is of thinner extent in the third coordinate direction than either dimension of said area and is subject in said discharge area to penetration by ionizing radiation, second electrode means spaced from said first electrode means in the third coordinate direction by an extent less than either dimension of said discharge area of said first electrode means said second electrode means having a discharge area coextensive with that of first electrode means, and said 15 second electrode means being in the form of an electroconductive coating on an insulating base member, an ionizable medium disposed in the space between said discharge areas and adapted to be ionized in a localized plasma pattern by and as a replica of a pattern of said penetrating ionizing radiation to thereby sustain an electrical discharge between the discharge areas of said first and second electrode means, and a plurality of at least three sensing electrodes in the form of rods electrically insulated from each of said first and second electrode means and 20 extending through said base member and second electrode means at respective points which are distributively spaced in said two coordinate directions to form a network of plasma sensing points, said network extending in both of said two directions, and the points thereof 25 being separated by straight line intervals lying within the bounds in said two directions of said discharge areas, said sensing electrodes terminating at a distance from said first electrode means which at the least is equal to the distance therefrom of said first electrode means, and said 30 sensing electrodes being insulated from said first electrode means by voids formed in said second electrode means in the respective localized areas thereof surrounding said sensing electrodes.
